6 Claims. (Cl. 118—41)

This invention relates to machines for placing gummed labels or stamps upon a mailing piece and particularly to an improved machine for applying individual labels or stamps from a sheet in which they are held in a plurality of parallel strips.

Stamps, gummed labels, address stickers, and the like are frequently and most economically manufactured in sheet form separated by lines of perforations. In order to apply individual stamps or labels to a surface such as an envelope or mailing piece from such a sheet, it is necessary to first separate the individual member or unit from the sheet, moisten it and then apply it. These steps often nullify the savings made through the use of inexpensive sheets.

It has been known to place such sheets in a machine, sever them into short strips, and then feed them into knives which cut individual units from the strips. Other known devices place the sheets on a traveling carriage which advances them one by one into a cutting position much as a typewriter advances a page for imprinting. Still other prior art devices sever individual stamps or labels by means of a moving knife and convey them to a moistening and applying station.

All of the above mentioned prior art devices are complicated, prone to mechanical failure, large and expensive.

The invention herein, in effect, converts a sheet of stamps or labels into an elongated helical strip of stamps or labels by directing the sheet through a skewed path. The leading stamp or label is thus fed into the cutting and moistening station laterally offset with respect to the next adjacent strip of stamps or labels which form the next turn of the helix. Successive stamps or labels are thus presented to the cutting and moistening station without further lateral motion of the sheet and without the need for first severing the sheet into strips.

Accordingly it is an object of the present invention to provide a highly simplified stamp or gummed label applying or dispensing machine.

Another object of the present invention is to provide a machine which will accept labels or stamps in sheet form and dispense them as individual units.

Still another object of the present invention is to provide a stamp or label dispensing device which will operate over a prolonged period without failure due to gumming or jamming.

A further object of the present invention is to provide a label applying and dispensing device which can be stopped at any time and resumed without sticking or dispensing a plurality of labels.

A further object of the present invention is to provide a label or stamp dispensing machine capable of feeding successive sheets into the machine for continuous operation.

An object of the present invention is to provide a compact, light, and inexpensive stamp or label applying and dispensing machine.

A feature of the present invention is its use of a skewed table to lead the sheet of stamps or labels into a path whereby they are formed into a helix.

Still another feature of the present invention is its feed-

2

ing means for advancing individual stamps or labels into the cutting or dispensing position.

A further feature of the present invention is its unit severing and moistening means.

Another feature of the present invention is its highly simplified construction employing a minimum number of parts for dispensing and applying individual units from a sheet to a mailing piece.

The invention consists of the construction, combination and arrangement of parts and the steps of the method as herein illustrated, described and claimed.

In the accompanying drawings, forming a part hereof are illustrated two forms of embodiment of the invention, and in which:

15 FIGURE 1 is a top plan view of a complete embodiment of a label applying machine made in accordance with the present invention.

20 FIGURE 2 is a longitudinal section taken on line 2—2 in FIGURE 1 looking in the direction of the arrows.

25 FIGURE 3 is a somewhat diagrammatic top plan view on a reduced scale illustrating the manner in which a sheet of labels is converted into a helical strip of labels.

30 FIGURE 4 is a longitudinal section taken on line 4—4 in FIGURE 3 looking in the direction of the arrows.

35 FIGURE 5 is a view in front elevation of the label applying machine shown in FIGURE 1.

40 FIGURE 6 is a sectional view taken on line 6—6 in FIGURE 5 looking in the direction of the arrows.

45 FIGURE 7 is a fragmentary view somewhat enlarged of the moistening portion of the device shown in FIGURES 1 and 5.

50 Referring to the drawings, and particularly to FIGURES 1, 2 and 3, 10 indicates a label dispensing and applying machine having a table 11 to receive thereon one or more sheets 12 of labels 13. The sheet 12 is scored or perforated as indicated at 14 in FIGURE 3 to divide the sheet into individual labels which are gummed on one side in the well known manner.

55 A skewed guide 15 secured at each side to a frame 41 is disposed adjacent the table 11 and has spaced flat top and bottom label receiving surfaces 16 and 17 thereon. The top label receiving surface 16 is on the same plane as the table 11 so that the sheets 12 can be slid from the table 11 directly on to the top surface 16 of the guide 15. The guide 15 is formed with rounded front and rear edges 18, 19 which interconnect the top and bottom label receiving surfaces 16, 17. The front and rear edges 18, 19 are parallel to each other but angularly disposed with respect to the longitudinal axis of the table 11.

60 As a result of the angular disposition of the guide 15 with respect to the table 11, and as will be apparent from an examination of FIGURE 3, the sheet 12 having the labels 13 therein is led around the rounded front and rear edges 18, 19 and assumes a position upon the guide 15 wherein the labels 13 are disposed in a substantially continuous helical path around the guide 15. As shown in FIGURE 3 the sides of the skewed guide 15 and the spacing of the front and rear edges 18, 19 is such that the sheet 12 will lie with its leading edge 20 and its trailing edge 21 in an abutting relationship after the sheet 12 has been completely wrapped around the guide 15. As the leading edge of the sheet 12 approaches the cut off station 22 of the label dispensing machine 10, the first label indicated at 23 in FIGURE 3 will be laterally offset from the next adjacent line of labels indicated at 24. As the sheet 12 is fed around the table 11 in the hereinafter more fully set forth manner, successive labels 13 will appear at the cut off station 22 due to the generally helical arrangement of the labels, brought about by the skewed guide 15 over which the sheet is slid.

65 A top guide plate 25 is carried by the label dispensing

machine above the skewed guide 15 and spaced therefrom. The top guide plate 25 has an upwardly directed flap 26 which directs the sheet 12 beneath the plate 25 and across the flat label receiving surface of the skewed guide 15. A bottom guide plate 27 is carried beneath the skewed guide 15 and spaced therefrom a distance just large enough to permit the sheet 12 to slip freely between the guide plate 27 and the skewed guide 15. The front of the bottom guide plate 27 is curved upwardly as indicated at 28 in FIGURES 2 and 4, to receive the leading edge 20 of the sheet 12 and guide it downwardly between the bottom label receiving surface 17 of the skewed guide 15 and the bottom guide plate 27. A small block 29 is secured beneath the table 11 at the opposite end of the skewed guide 15. The block 29 is formed with an arcuate front surface 30 which is spaced from the rounded rear edge 19 of the skewed guide 15 as shown in FIGURES 2 and 4. The arcuate surface 30 directs the leading edge 20 of the sheet 12 upwardly and between the top guide plate 25 and the flat top label receiving surface 16 of the skewed guide 15 to give the sheet 12 the configuration shown in FIGURE 3.

The top guide plate 25 is cut away as indicated at 31 and 32 in FIGURE 1 to receive therethrough the sheet feeding pads 33. The pads 33 are preferably made of some suitable resilient material such as sponge rubber or the like and are secured to a plate 33a attached to the bottom of blocks 34. The blocks 34 are bored as indicated at 35 to receive therein eccentric cams 36. The cams 36 are keyed to an elongated shaft 37 which is driven by means of the crank 38 or some other suitable power source. The shaft 37 is journaled within plates 39 secured at each side of the label dispensing machine 10, to spring loaded arms 66.

In order to prevent the shaft 37 from flexing between the plates 39 there is provided an arm 40 best shown in FIGURES 2 and 5 which is secured to the frame 41 of the label dispensing machine 10 by means of a bracket 42. The arm 40 overlies the shaft 37 and carries a spring loaded plunger 43 which rides upon the shaft 37. Shaft deflection is thus held to a minimum during the operation of the machine.

As the crank 38 is turned the eccentric cams 36 move the blocks 34 from the rear of the cut away slots 31, 32 toward the front of the said slots causing the pads 33 to slide the sheet 12 forward in the direction of the cut off station 22. As the feeding pads 33 reach the front of the slots 31, 32 the eccentric cams 36 raise the pads off the sheet 12 and carry the pads 33 rearwardly and then down again into contact with the sheet to repeat the feeding cycle. It will be understood that the travel of the pads 33 will be governed by the size and configuration of the cams 36 in such a manner that for each rotation of the cams one complete label distance will be advanced by the sheet 12 or, if desired the sheet may be moved the desired distance by two or three complete rotations of the cams 36.

As the leading label 23 on the sheet 12 reaches the cut off station 22 it will overlie a resilient pad 44 best shown in FIGURE 1. The resilient pad 44 is secured to the end of a pivotally mounted arm 45. The label 23 will also lie in the path of a cut off knife 46 carried on the end of a bar 47. The bar 47 is swingably secured to the label dispensing machine 10 at 48 and when brought down upon the label severs it from the sheet 12 in the manner of a steel rule die. The bar 47 also supports a moistening device 49 best shown in FIGURE 7. The moistening device 49 consists of a small reservoir 50 within which a liquid such as water may be carried. The liquid 51 is led from the reservoir 50 through a small tube 52 which traverses the knife support 53 on the end of the bar 47. As the knife 46 is brought down to sever the label from the sheet, a droplet of water or other liquid 51 will flow from the tube 52 on to the gummed surface of the label for moistening purposes.

Where the liquid is applied from the top as shown in FIGURES 5 and 7 the sheet is fed into the machine 10 with the gummed surface up. However, it is within the purview of the present invention to apply moisture to the label from the bottom using other moistening means than those illustrated in FIGURES 5 and 7.

Two small spring loaded screws 54 are carried by the knife support 53 as shown in FIGURE 5. The screws 54 are forced upwardly into the knife support 53 as the knife 46 is brought into contact with the label. The screws 54 hold the severed labels against the pad 44 as the knife is withdrawn leaving the label upon the pad 44. The arm 45 can then be tilted upwardly as shown in dashed lines in FIGURE 2 to bring the label against a mailing piece 55 for attachment thereto. After the label has been brought into contact with the mailing piece 55 the arm 45 is lowered to its original position and the shaft 37 rotated by the crank 38 to bring the next label into the cutting station 22. The cutting and label applying operation is then repeated and successive operations continued until all of the labels on the sheet 12 have been used up.

As the last strip of labels is fed into the cutting station 22 another sheet (not shown) may be fed into the machine from the rear of the table 11. A feed arm 55 best shown in FIGURE 2 is provided at the rear of the table 11 for this purpose. The feed arm 55 has a rubber roller 56 at the end thereof which bears against the topmost sheet of labels held thereunder. A small knifelike member 57 is carried by a bracket 58 at the rear of the table 11 and serves to retain the sheets of labels placed thereunder. When the rubber roller 56 is moved forward by the feed arm 55 it pulls the topmost sheet clear of the knifelike member 57 which nevertheless retains the remainder of the sheets on the table 11. In this manner one sheet at a time can be fed into the label dispensing and applying machine.

It will be apparent that the above device can be motor driven and made completely automatic without departing from the spirit of the present invention. In addition, the highly simplified structure of the devices makes it possible to operate them at relatively high speed. Since the labels are not moistened until they are ready to be severed from the sheet there is no danger of gumming due to moisture getting into the attached label.

The spring loaded arms 66 hold the pads 33 against the sheet 12 throughout their travel within the slots 31, 32 despite the rotary motion of the cams 36 to provide a positive feeding action for the sheet.

Having thus fully described the invention, what is claimed as new and desired to be secured by Letters Patent of the United States, is:

1. A device for dispensing individual units from a sheet made up of a plurality of said units secured together in rows at their adjacent margins comprising a frame, means thereon to initially direct said sheet longitudinally in a given path, a guide having spaced parallel curved sides held by said frame in said path and skewed with respect to said path, means to direct the sheet around the spaced parallel sides of the guide and thereby lead the rows of units in a substantially helical path around the guide, means to helically advance the sheet around the guide and means to sever individual units from the sheet.

2. A device for dispensing individual units from a sheet made up of a plurality of said units secured together in rows at their adjacent margins comprising a frame, means thereon to initially direct said sheet in a given path, a guide having spaced parallel curved sides held by said frame in said path and skewed with respect to said path, means including a top and bottom guide plate spaced from the skewed guide to direct the sheet around the spaced parallel sides of the guide and thereby lead the rows of units in a substantially helical path around the guide, means in frictional contact with the sheet to helically advance the sheet around the guide and knife means to sever individual units from the sheet.

3. A device according to claim 2 in which the sheet advancing means comprises a shaft carried above the guide, a plurality of sheet engaging members on the shaft and means to rotate the shaft to drive the sheet engaging members.

4. A device according to claim 2 in which the sheet advancing means comprises a shaft carried above the guide, spaced spring loaded arms on each end of the shaft secured at one end to the frame supporting the shaft and yieldably urging it toward the guide, a plurality of resilient sheet engaging members, a block supporting each resilient member, cam means in driving engagement with each block on the shaft and means to rotate the shaft to drive the cams and actuate the sheet engaging members.

5. A device for dispensing individual units from a sheet made up of a plurality of said units secured together in rows at their adjacent margins comprising a table to receive the sheets, a frame adjacent the table to receive the sheets from said table, and means thereon to initially direct said sheets in a given path, a guide having spaced substantially parallel curved sides positioned transversely of said path and skewed with respect thereto, means including a top and bottom guide plate spaced from the skewed guide to direct the sheet around the spaced parallel sides of the guide and thereby lead the rows of units in a substantially helical path around the guide, means in frictional contact with the sheet to hel-

ically advance the sheet around the guide and knife means to sever individual units from the sheet.

6. A device for dispensing individual units from a sheet made up of a plurality of said units secured together in rows at their adjacent margins comprising a frame, means thereto to initially direct said sheet in a given path, a guide having spaced parallel curved sides held by said frame in said path and skewed with respect to said path, means including a top and bottom guide plate spaced from the skewed guide to direct the sheet around the curved sides of the guide and thereby lead the rows of units in a substantially helical path around the guide, means in frictional contact with the sheet to helically advance the sheet around the guide, knife means to sever individual units from the sheet and means to apply moisture to the unit as it is severed.
